UNITED STATES PATENT OFFICE

115,918

DESIGN FOR A GARMENT HANGER

James F. Fewster, Trenton, N. J.

Application April 14, 1939, Serial No. 84,297

Term of patent 3½ years

To all whom it may concern:

Be it known that I, James F. Fewster, a citizen of the United States, residing at Trenton, Mercer County, New Jersey, have invented a new, original, and ornamental Design for a Garment Hanger, of which the following is a specification, reference being had to the accompanying drawing, forming a part thereof, in which

Fig. 1 is a front elevational view of a garment hanger showing my new design; and

Fig. 2 is a top plan view thereof. The dominant feature of the design is shown in full lines.

I claim:

The ornamental design for a garment hanger, substantially as shown and described.

JAMES F. FEWSTER,
